UNITED STATES PATENT OFFICE.

WALTER H. CLARKE, OF LOS ANGELES, CALIFORNIA.

BATH-TUB MAT.

1,201,256.

Specification of Letters Patent. Patented Oct. 17, 1916.

Application filed December 6, 1915. Serial No. 65,268.

To all whom it may concern:

Be it known that I, WALTER H. CLARKE, a citizen of the United States, residing at Los Angeles, in the county of Los Angeles 5 and State of California, have invented a new and useful Bath-Tub Mat, of which the following is a specification.

This invention relates to a mat designed to be placed on the bottom of a bath tub so 10 that it may be stood or sat upon while bathing and will prevent the bather from slipping, the mat being constructed to hold firmly on the bottom of the tub.

The primary object of this invention is to 15 provide a tub mat of the character described which is simple as to construction, inexpensive to manufacture and constructed so that suction or vacuum cups are provided on the under side thereof to hold it against slipping.

Other objects and advantages will appear from the subjoined detail description.

The accompanying drawings illustrate the invention.

25 Figure 1 is a top plan view of a bath tub showing the mat in position; Fig. 2 is a longitudinal sectional view taken on line 2—2 of Fig. 1; and Fig. 3 is a bottom plan view of the mat.

30 Referring to the drawings, 1 designates a bath tub of the ordinary type and 2 my mat.

The mat 2 is preferably formed of a relatively thin, soft, flexible and resilient body portion, and while shown in an oval shape 35 may be of any shape, size or thickness desired. The upper surface is roughened or corrugated as at 3 and the corrugations may be formed by ribbing or indenting the material of which the mat is formed. Various ornamental designs may be formed by 40 arrangement of the corrugations as will be seen with reference to the drawings.

A depending peripheral resilient flange or rib 4 is formed on the mat and is adapted 45 to engage the tub or other surface upon which the mat is placed to form a suction or vacuum cup and hold the mat against slipping. There are provided other suction cups which are formed by circular or other 50 shaped resilient ribs or flanges depending from the under face of the mat, for example, as shown in the accompanying drawings, a large cup 5 is located in the center of the mat and groups of smaller cups 6 are 55 formed on opposite sides of the cup 5.

In use, the mat is placed on the bottom of

the tub and as it is flexible will accommodate itself to the tub. The suction cup provided by the flange or rib 4 and the cups 5 and 6 will cause the mat to be held against slipping upon the tub bottom and also provide air cushions which will increase the resiliency of the mat so that it may serve as a soft and comfortable seat. This mat may be placed in position in the tub after or before the water is run into the tub and will not be effected or its grip upon the tub released by the presence of water in the tub. The bather may sit upon the mat or step upon it in getting into or out of the tub and avoid slipping in this way. The corrugated upper surface of the mat prevents the bather from slipping relative to the mat.

In having the flange or rib 4 formed on the under face of the mat at the periphery thereof and the ribs or flanges forming the cups 5 and 6 located at the center and between the center and ends, the body of the mat will be supported in spaced relation to the bottom of the tub and the air cushions formed by the suction cups increase the resiliency of the mat to the extent that a springy and soft seat is provided.

It is understood that the invention is not limited to the exact construction shown in the drawings and described above, but that deviations therefrom may be made within the spirit and scope of the invention.

I claim:

1. A bath tub mat comprising a flexible resilient body having a depending, continuous resilient flange at the periphery thereof adapted to engage the bottom of a bath tub and space the body therefrom and a plurality of substantially circular flanges formed integral with and depending from the underface of the body and providing suction cups, all of said flanges having their lower edges located in the same plane.

2. A bath tub mat comprising a flexible resilient body having a depending resilient continuous flange at the periphery thereof and a circular flange formed integral with the underface of the body approximately centrally thereof and other circular flanges formed integral with the body on the underface thereof, said flanges, in combination with the body, providing suction cups, all of said flanges having their lower edges located in the same plane.

3. A bath tub mat comprising a flexible

resilient body portion, a depending resilient flange formed integral with the body portion at the periphery thereof, a circular flange formed integral with the underface and body centrally thereof, said first-named flange being continuous and suction cups formed integral with the body on the underface thereof, said cups having their opened

ends located in the same plane as the lower edges of the flanges.

Signed at Los Angeles, California, this 30th day of November, 1915.

WALTER H. CLARKE.
